COLLAPSIBLE-HANDLE CAN.

1,007,429.

Specification of Letters Patent. Patented Oct. 31, 1911.

Application filed January 23, 1907. Serial No. 353,689.

To all whom it may concern:

Be it known that we, ENRICO GIUSEPPE CANEPA, residing at Portici Vittorio Emanuele 4^a, Genoa, Italy, and GIUSEPPE OTTONE FU GIORGIO, residing in Quinto al Mare, Province of Genoa, Italy, both subjects of the King of Italy, have invented certain new and useful Improvements in Collapsible-Handle Cans, of which the following is

10 a specification.

The present invention relates to improvements in the manufacture of metallic vessels or cans, the object of said improvements being to produce a convenient article 15 at cheap price and arranged to be easily carried by minimizing the space occupied in packing. The above said results are obtained by forming the mouthpiece for pouring the liquid contained in the vessel in the 20 shell or body of same, and further by providing a yielding handle which, in packing the vessel, can be brought in contact with the body of the can, thus avoiding any projecting part.

25 Figures 1 and 2 of the annexed drawings, show, by way of example, two perspective views of a slightly pyramidal can provided with the improvements forming the object of this invention. Figs. 3 and 4 are horizontal cross sections of a conical shaped can. It will be understood though, that the invention is not confined to these particular forms of cans, but that it is applicable also to otherwise shaped vessels.

35 As the figures clearly show, the mouth piece 1 for pouring the liquid content of the vessel is formed in the body 2 of same, which can be made of a single piece of sheet metal, no soldering being required for attaching the mouth piece 1. The latter begins near the bottom 3 of the vessel and rises gradually until at the mouth of the vessel it projects its full height, thus better facilitating the outflow of the liquid.

40 The body of the vessel is formed of a single sheet of metal having an approximately rectangular shape and which, when two opposite edges are soldered, or otherwise connected together, forms a portion of a cylinder open at both ends. The nozzle or mouth piece 1 is then formed in the cylinder which undergoes thus a change in its external appearance and assumes a conical

shape, the small base being at the top of the vessel where the nozzle projects farthest. 55 When the body of the vessel is obtained from a rectangular sheet the dimension of the nozzle at the bottom of the vessel accounts for the difference between the two bases of the vessel, which assume thus a 60 conical shape.

The body of the can can remain conically shaped, that is it can preserve a circular cross section, decreasing from the base to the top, as shown in Figs. 3 and 4, or, if 65 required, the cross section can be changed to a polygonal one, and the can made slightly pyramidal, as shown in Figs. 1 and 2.

The vessel is fitted with a handle 4, which in the embodiment shown in the drawing 70 and relating to a roughly prismatical can, is attached on the face opposite that whereon is formed the mouth piece. But any other position can be selected according to the particular circumstances. The handle 4 is 75 yieldingly attached at 5, near the bottom of the vessel, and at the other end 6 is bent at right angle and can slide on the cover 7 passing under a loop 8. Thus, in carrying the vessel packed, the handle 4 is maintained in contact with the body of the vessel and its arm 6 keeps the cover 7 closed as shown in Fig. 1.

A can as above described, has the advantage that in carrying the same packed with 85 the handle in contact with the body, the can does not require more room than the larger base at the bottom, if the projection of the mouth and of the handle has been conveniently regulated. When unpacked the handle 90 springs back into the position shown in Fig. 2, so as to render easy the lifting of the can.

We claim—

1. A can of the character specified, comprising a quadrangular body gradually decreasing in cross section from below upward, a handle yieldingly attached at one end to the can, and a loop on the cover through which slides the other end of the 100 handle.

2. A can of the character specified, comprising a quadrangular body having a flat bottom and gradually decreasing in cross section from below upward, a handle yieldingly attached at one end to the can, near its

base, a loop on the cover through which the other end of the handle slides, and a spout on the opposite side of the body from the handle, a perpendicular line from the outer-
5 most portion of the spout to the plane of the base falling within the periphery of the base.

In testimony whereof we have hereunto

set our hands in the presence of two wit-
nesses.
